Des. 214,405
Patented June 10, 1969

214,405

TAPE DISPENSER

Jack Fairchild Fleming, 28 Woodcrest Road,
Boonton, N.J. 07005

Filed Sept. 3, 1968, Ser. No. 13,363

Term of patent 14 years

Int. Cl. D19—02

U.S. Cl. D74—1

FIG. 1

FIG. 2

FIG. 3

FIG. 4

FIG. 5

FIG. 1 is a side elevational view of a tape dispenser embodying my new design and shown on an enlarged scale, the opposite side being similar in appearance;

FIG. 2 is a top plan view thereof;

FIG. 3 is a rear end view thereof;

FIG. 4 is a front end view thereof; and

FIG. 5 is a bottom plan view thereof.

I claim:

The ornamental design for a tape dispenser, substantially as shown and described.
